UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

BLANKET-CYLINDER FOR PRINTING-PRESSES.

1,306,095.

Specification of Letters Patent. Patented June 10, 1919.

Original application filed April 26, 1916, Serial No. 93,695. Divided and this application filed June 13, 1917. Serial No. 174,555.

To all whom it may concern:

Be it known that I, HENRY F. BECHMAN, a citizen of the United States, residing at Battle Creek, in the county of Calhoun and State of Michigan, have invented certain new and useful Improvements in Blanket-Cylinders for Printing-Presses; and I hereby declare that the following is a full, clear, and exact description thereof, reference being had to the accompanying drawings, which form part of this specification.

This invention is a novel improvement in printing machinery and has particular reference to the "blanket" or impression cylinders of rotary presses; and its object is to practically obviate the "spring" of such cylinders, which has heretofore been a source of great trouble in high speed rotary presses, and also to locate the blanket adjusting devices exterior to the cylinder bearings and gears, so that they will be readily accessible from the outside of the side or end frames or bearings in which the cylinder is journaled, instead of said devices having to be located and operated intermediate the ends of the cylinder and the side frames or bearings in which the cylinder trunnions are mounted. This construction enables the press as a whole to be narrowed in width or shortened in length, according to whether the cylinders are arranged transversely or longitudinally thereof.

The present invention is a division of my application Serial No. 93,695 filed April 26, 1916, for cylinders and plate clamping devices for rotary printing presses.

In the present invention I dispense with any cylinder trunnions or shafts, and journal the ends of the impression cylinder directly in the bearings, and this enables me to arrange the adjusting devices for the blankets at the end of the cylinder and outside of the bearings or frame.

The novel features of the invention will be hereinafter explained in detail with reference to the accompanying drawings so that others skilled in the art will be able to readily adopt and use the same; and the essential features and novel combinations of parts for which protection is desired are set forth in the claims following said description.

In said drawings:

Figure 1 is a detail side elevation of part

of a press, showing a printing couple comprising a plate and impression cylinder journaled in bearings therein.

Fig. 2 is an enlarged end elevation of the impression cylinder, the cylinder gear being partly broken away.

Fig. 3 is an enlarged vertical section of part of the impression cylinder on line 3—3 Fig. 2.

The plate cylinder 1 and impression cylinder 5 may be in general similar to the cylinders now in use, with the important exception that the usual supporting shaft or supporting trunnions are dispensed with, and instead each cylinder is made long enough to practically extend through the side frames of the press. The ends of the cylinders form its journals and may be of the same diameter as the body thereof, but are preferably slightly reduced. This enables the press to be narrowed or shortened because of the absence of end trunnions or shafts on the cylinders; and also enables the devices by which the plate clamps or the blanket adjusting devices are operated to be extended directly through the ends of the cylinder and bearings to the outside of the press frame.

As shown the end of the plate cylinder 1 is slightly reduced, and is journaled in a box 2. The ends of the impression cylinder 5 are also slightly reduced, and journaled in boxes, as 2^a. The boxes 2 and 2^a may be adjustably mounted in the frame 3 of the machine.

The boxes 2 and 2^a may be of any suitable construction and provided with any suitable means for adjusting the cylinders toward or from each other as usual in printing presses; the journal boxes being enlarged to properly accommodate the ends of the cylinders journaled therein.

The impression or blanket cylinder 5 may be constructed in general like the ordinary impression cylinders except that it is trunnionless, or of substantially uniform diameter throughout, preferably having its ends slightly reduced to form trunnions as at 5^a where they are journaled in boxes 2^a, the ends of the cylinder projecting through such boxes.

Said cylinder 5 is provided with the usual openings or slots 5^b in which are mounted the shafts 7 and 8 to which the ends of the

blankets or tympans are attached as usual. Owing to the novel construction of the impression cylinder the shafts 7 and 8 can extend directly straight out through the large 5 journals of the cylinder to the outer end thereof and can be manipulated from the outside of the press frame. On one end of cylinder 5 a gear 6 is attached, and the outer ends of the shafts 7 and 8 may be journaled 10 in openings in the web 6^a of the gear 6, which may be fastened to the end of the cylinder in any suitable manner, and is shown as secured thereto by bolts 6^b.

The outer ends of the shafts 7 and 8 may 15 be squared as at 7^a, 8^a for engagement with a suitable wrench by which said shafts can be turned; and they may also be provided with any suitable devices for locking such shafts when adjusted; such as ratchets 7^b, 20 8^b, engaged by pawls 7^c, 8^c.

The slots 5^b in cylinder 5 may be staggered and the plates on the plate cylinder staggered, in the well known manner. In the example shown the impression cylinder 25 5 is adapted to coöperate with "staggered" plates on the plate cylinder, and it is therefore provided with two sets of blanket or tympan adjusting devices 7 and 8.

The cylinders may be made solid, but are 30 preferably made hollow and ribbed, as indicated in dotted lines, in the usual manner to enhance their stiffness while reducing their weight.

It will be seen that the blankets can be 35 readily adjusted from the outer side of the bearing or frame and outer end of the cylinder; this feature is of great practical convenience to the pressman, and it enables the press to be correspondingly narrowed in 40 width or shortened in length (according to the disposition of the cylinders therein) as compared with the heretofore known cylinders wherein the adjusting devices had to be arranged adjacent the inner ends of the 45 cylinder trunnions, and to the inside of the bearings and frame.

What I claim is:

1. In combination, an impression cylinder having an end journal, and blanket adjusting devices extending through the cylinder journal and accessible from the outer end of 50 the journal.

2. In combination with a press frame and bearings; of an impression cylinder having

an end journal of substantially the same diameter as the body of the cylinder; and 55 blanket adjusting devices extending through the journal of the cylinder and the bearing, and accessible from the outer side of the bearing and frame.

3. In combination, an impression cylinder having end journals; and a blanket adjusting shaft extending straight outward through the ends of the cylinder and the journal thereof and accessible from the outer side of 60 the bearing.

4. In a printing press, a trunnionless impression cylinder having a body and journals of substantially the same diameter and a blanket adjusting shaft extending outward through the end of the cylinder and a journal thereof and eccentric to the axis thereof and accessible from the outer end of 65 the journal.

5. In combination with a press frame and 70 bearings; of an impression cylinder having a body and end journals all of substantially the same diameter and journaled in and extending through said bearings; and blanket adjusting devices extending through one end 75 of the cylinder and its journal and the bearing, and accessible from the outer side of the bearing and frame.

6. In combination; a trunnionless impression cylinder having a body and end journals all of substantially the same diameter; bearings in which the cylinder is journaled; the journals of the cylinder extending through said bearings; a driving gear on one end journal of the cylinder; and blanket adjusting devices extending through the gear end journal of the cylinder and accessible 80 from the outer side of the bearing.

7. In combination, a trunnionless impression cylinder having a body and end journals all of substantially uniform diameter; bearings on the frame in which the cylinder is journaled, a gear attached to one journal of the cylinder outside the bearing; and a pair of parallel blanket adjusting shafts 90 extending through one journal of the cylinder eccentric to the axis thereof and through its bearing and said gear, and accessible from the outer side of the press frame, substantially as described.

In testimony that I claim the foregoing as my own, I affix my signature.

HENRY F. BECHMAN.
